ATTORNEY

UNITED STATES PATENT OFFICE.

HARVEY HUBBELL, OF BRIDGEPORT, CONNECTICUT.

FLUSH RECEPTACLE.

1,275,690.

Specification of Letters Patent. Patented Aug. 13, 1918.

Application filed June 17, 1915. Serial No. 34,630.

To all whom it may concern:

Be it known that I, HARVEY HUBBELL, a citizen of the United States, residing at Bridgeport, county of Fairfield, State of Connecticut, have invented an Improvement in Flush Receptacles, of which the following is a specification.

This invention relates more especially to flush receptacles and has for its object to provide a device of this character comprising a body, a top block and a base or adjustment plate which shall be so constructed that the top block may be removed without disturbing the base or adjustment plate, which for the purposes of this specification I will term the base plate, although it is shown in connection with the adjusting means described and claimed in my pending application, Serial No. 32,080, filed June 20, 1915.

My present construction enables the operator to install the receptacle in an outlet box or wall with only the face plate removed and without attaching the wires and then, by removing the top block, to attach the wires to the binding screws, or when examination of the connections is required, it may be effected by simply removing the face plate and the top block and without disturbing the base plate or the body. Further advantages of my present construction are that it enables me to locate the binding screws at such a distance below the base plate as to render short circuiting impossible and to leave the binding screws covered by the top block.

With these and other objects in view, I have devised the novel structure which I will now describe, referring to the accompanying drawing forming a part of this specification and using reference characters to indicate the several parts.

Figure 1 is an elevation of a duplex receptacle with the face plate removed;

Fig. 2 an elevation with both face plate and top block removed;

Fig. 3 is a side elevation partly in section on the line indicated by 3 in Fig. 1, looking in the direction of the arrow;

Fig. 4 a section on the line 4—4 in Fig. 2, looking in the direction of the arrows, show-

ing the position of the binding screws and showing the top block in place;

Fig. 5 an end view;

Fig. 6 a view of a single plug receptacle being a slight modification of the structure 55 illustrated in Fig. 2, and

Fig. 7 is a view of a top block of the type employed with the structure of Fig. 6.

10 denotes the body, 11 the top block and 12 the base plate. The top block is provided 60 with a hub or hubs 13 provided with slots to receive knife blade contacts (not shown). The face plate specifically forms no portion of the present invention and is indicated by dotted lines only in Fig. 4. The face plate 65 may be secured to the base plate in any suitable manner, as by screws or by means of spring attaching fingers which pass through openings 14 in the base plate, as in my pending applications, Serial No. 11,391, filed 70 March 1, 1915, and 61,923, filed November 17, 1915. The base plate is made wide enough to overhang the recess for the device and is provided with a central opening 15 which receives the top block freely and permits its convenient insertion or removal, the top block being secured to the body by 75 screws 16. Integral with the base plate 12 at the openings 14 are struck-out lugs 14^a which serve the same purpose as the corresponding lugs shown and described in my applications just above referred to in attaching the said base plate to another part. At the ends of the base plate are inwardly extending flanges 17, the ends of which engage 80 the top of the body, and extending from the flanges are arms 18 having angle lugs 19 at their inner ends, said lugs lying in recesses 20 in the ends of the body. The base plate is secured to the body by screws 21 in the 85 back of the body which engage the angle lugs. The device as a whole may be secured to an outlet box, a baseboard, or a wall in any suitable manner, but preferably by the means described and claimed in my pending 90 application Serial No. 32,080, filed June 4, 1915, and which I have illustrated in this case. 22 denotes adjusting ears which lie in the recesses and are provided with shanks 23 which extend outward through slots 24 100

in the flanges and arms of the base plate and are secured to an outlet box, baseboard or wall by screws (not shown) passing through slots in extensions from said shanks forming 5 attaching ears 25 at the outer ends of the shanks. 26 denotes adjusting screws which pass through carrying lugs 27, extending inwardly from the flanges of the base plate, and have threaded engagement with the adjusting ears 22. In installing, after the attaching ears have been secured in place, the base plate is placed in engagement with the face of the baseboard or wall and then the adjusting screws are turned inward to secure 10 it in place, it being understood of course that the adjusting ears do not necessarily lie in the same plane. The base plate and body must lie parallel with the face of the wall, but it is immaterial whether or not recesses 15 in a wall or baseboard for the attaching ears are of the same depth, or whether an outlet box, if used, is set exactly parallel with the face of the wall or baseboard or slightly obliquely thereto.

25. 28 denotes spring contacts adapted for engagement by knife blade contacts (not shown) and 29 binding screws. In the form illustrated in Figs. 1 to 4 inclusive, that is, in a duplex receptacle, the spring contacts are secured to opposite ends of connecting plates 30 secured to the body by screws 31, and the binding screws are placed intermediate the spring contacts on each plate. The form illustrated in Fig. 6, that 25 is, a single plug receptacle, differs only in that plates 32 each carry a binding screw and one spring contact only. The advantages of the removable top block are the same in both forms. The wires may be 30 connected after the receptacle is installed, the connections may be examined at any time, the binding screws are placed at a safe distance below the face plate and the binding screws are always covered in use 35 by the top block.

Having thus described my invention I claim:—

1. A device of the character described comprising a body, a base plate secured thereto and shaped to overhang a wall recess, said base plate having a central opening, a removable top block of a size to be passed through said opening without disturbing the base plate, and means for detachably connecting said top block to said body.

2. A device of the character described comprising a body, a base plate secured thereto and shaped to overhang a wall recess, said base plate having a central opening and being provided with inwardly extended flanges engaging said body, a removable top block of a size to be passed

through said opening without disturbing the base plate, and means for detachably connecting said top block to said body.

3. A device of the character described comprising a body, a base plate secured thereto and shaped to overhang a wall recess, said base plate having a central opening, a removable top block of a size to be passed through said opening without disturbing the base plate, means for detachably connecting said top block to said body, and means for adjustably supporting said base 75 plate to permit the same to rest flat against the surface surrounding said wall recess.

4. A device of the character described comprising a body, a base plate lying separated from the body and having an opening and inwardly extending flanges engaging the body, arms extending from the flanges and slots in said arms and flanges, adjusting screws in said plate, adjusting ears engaged by said screws and provided with shanks 85 passing through the slots and with attaching ears, and a removable top block adapted to be passed through the opening in the base plate and secured to the body.

5. A device of the character described comprising a body, a base plate lying separated from the body and having an opening and inwardly extending flanges engaging the body, arms extending from said flanges and having angle lugs secured to the body, 95 said arms and flanges being provided with slots, adjusting screws in said plate, adjusting ears engaged by said screws and provided with shanks passing through the slots and with attaching ears, and a removable 100 top block adapted to be passed through the opening in the face plate and secured to the body.

6. A device of the character described comprising a body, a base plate secured to 105 said body and wider than the same to provide wall engaging portions, adjusting screws carried by said plate, adjusting ears engaging said screws to support said plate, said adjusting ears permitting adjustment 110 to allow the flanges to rest against said wall, said base plate having a central opening, a removable top block of a size to be passed through said opening without disturbing the base plate, and means for detachably connecting said top block to said body.

7. A device of the character described comprising a body having recesses in its ends, a base plate adapted to engage a wall and having flanges engaging the body, arms 120 extending from the flanges and secured to the body, said flanges and arms being slotted, adjusting ears lying within the recesses and having shanks passing through the slots and provided with attaching ears, 125 adjusting screws engaging the base plate

and the adjusting ears, and a removable top block adapted to be passed through the base plate and secured to the body.

8. A device of the character described comprising a body, a base plate secured thereto and shaped to overhang a wall recess, said base plate having a central opening and being provided with means for securing a face plate thereto, a removable top

block of a size to be passed through said opening without disturbing the base plate, means for detachably connecting said top block to said body, and adjustable means for attaching said base plate to a wall to permit the same to lie flat against said wall. 15

In testimony whereof I affix my signature.

HARVEY HUBBELL.
